FOUNTAIN PEN BLOTTER

Louis Dunning, Bloomington, Ill.

Application December 26, 1934, Serial No. 759,278

4 Claims. (Cl. 120—26)

This invention relates to a blotter and has for the primary object the provision of a device of this character which will provide an attachment to a fountain pen so that the user of the pen will have readily accessible a blotter, whereby writing made by the pen may be easily and quickly blotted, obviating the necessity of having to await drying of the ink or looking for a blotter which, in many instances, is displaced or not convenient to find.

With these and other objects in view, this invention consists in certain novel features of construction, combination and arrangement of parts to be hereinafter more fully described and claimed.

For a complete understanding of my invention, reference is to be had to the following description and accompanying drawing, in which

Figure 1 is a vertical sectional view illustrating a blotter in the form of an attachment applied to a fountain pen and constructed in accordance with my invention.

Figure 2 is a fragmentary vertical sectional view illustrating the attachment with the blotter element thereof positioned for operation.

Figure 3 is a sectional view taken on the line 3—3 of Figure 2.

Figure 4 is a sectional view taken on the line 4—4 of Figure 2.

Figure 5 is a sectional view taken on the line 5—5 of Figure 2.

Figure 6 is an end elevation showing the blotting element in operative position.

Figure 7 is a detail sectional view showing the means of limiting the movement of the blotting element into either operative or inoperative position.

Figure 8 is a detail view partly in section showing the blotting element in inoperative position.

Figure 9 is a perspective view showing the blotting element made in tubular formation.

Figure 10 is a perspective view showing a roll for the tubular blotter.

Figure 11 is a perspective view illustrating a supporting shaft, while Figure 12 shows the supporting block.

Referring in detail to the drawing the numeral 1 indicates a conventional type of fountain pen including the usual removable cap 2 and to adapt my invention to the fountain pen the cap 2 has its end wall removed so as to receive a tubular extension 3 of the attachment. The extension has frictional contact with the walls of the contact and being of tubular shape permits the pen or writing point of the instrument to enter when

the cap 2 is applied to the barrel of the fountain pen. A body 4 is integral with the extension 3 and of a diameter equal to the diameter of the cap 2 and has a chamber 5 opening outwardly through its free end to permit the mounting therein of a supporting block 6. The block 6 has frictional contact with the walls of the chamber 5 and is provided with a groove 7 to rotatably receive a shaft 8. The shaft 8, at one end, is provided with a lug or projection 9 operating in the chamber 5. The shaft operating in the groove 7 of the supporting block 6 arranges the shaft 8 eccentrically of the longitudinal axis of the chamber 5. The shaft is capable of a limited rotation in either direction. The rotation in either direction is limited by the lug 9 contacting with walls of the chamber 5. The shaft 8 is provided with oppositely arranged notches 10 and engaging in the notches is a spring-pressed plunger 11 carried by the supporting block 6. The plunger 11, when in engagement with one notch, will maintain the shaft against accidental rotation in one direction and will permit the shaft to be rotated manually to bring the plunger in engagement with the other notch so that said plunger will hold the shaft against accidental rotation in its latter-named position.

The shaft adjacent to one end of the groove of the supporting block is offset at right angles, as shown at 11', so that the portion 12 of the shaft, which forms a journal for a blotting element 13, is disposed in a plane laterally of the portion of the shaft which operates in the groove 7.

The blotting element 13 being mounted for rotation on the journal portion 12 of the shaft 35 may be positioned to either align with the body 4 or to be disposed laterally of the body 4, as shown in Figure 2, and when in the latter-named position it may be readily brought into engagement with a writing specimen for the purpose of absorbing the ink.

The blotting element 13 consists of a tubular shell 14 of absorbent material and is removably mounted on a roller-like element 15, the latter being journaled upon the portion 12 of the shaft 45 and retained thereon by a removable nut 16 having threaded engagement with the shaft. A groove 17 is formed in the element 15 and operating in the groove is a leaf spring 18, one end of which is anchored, as shown at 19, while the opposite end is free to slide in the groove. Normally the leaf spring projects slightly out of the groove to contact the inner wall of the shell 14 to retain the shell on the member 15 against accidental displacement.

,A cover or cap 20 engages over the body 4 with frictional contact and forms a closure for the blotting element when positioned in alignment with the body 4 or in an inoperative position.

- 5 The attachment when applied to an ordinary fountain pen does not materially alter the general appearance of the fountain pen except adding to its length and the attachment may be readily brought into use by simply removing the cap 10 20 and swinging the blotting element laterally of the body 4, as shown in Figure 2, and when in this position may readily be brought into contact with writing matter for the purpose of absorbing ink.
- 15 It is desirable that the absorbent material of the shell 14 at one end be notched to receive an extension at the other end of said material, as suggested by the illustration made in Figure 9, to prevent tearing or separation of the ends of 20 the material when cemented or otherwise secured together during the use of the device.

Having described the invention, I claim:

1. A blotter comprising a body having a chamber, a shaft eccentrically journaled in the chamber and having an offset journal portion, means for limiting the rotation of the shaft in either direction, and a blotter element mounted on the journal portion and adapted to be positioned laterally of said body portion or in alignment therewith, and means for retaining the shaft against accidental rotation when said blotter element is in either of its positions.
- 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450
2. A blotter comprising a body, a shaft ec-

centrically journaled to said body and having an offset journal portion, a roller rotatably mounted on the journal portion, a shell of absorbent material removably mounted on said roller, means for limiting the rotation of the shaft in either direction to permit positioning of the shell laterally of the body or in alignment therewith.

3. A blotter comprising a body, a shaft eccentrically journaled to said body and having an offset journal portion, a roller rotatably mounted 10 on the journal portion, a shell of absorbent material removably mounted on said roller, means for limiting the rotation of the shaft in either direction to permit positioning of the shell laterally of the body or in alignment therewith, means 15 to engage said shaft for holding the latter against accidental rotation in either of the positions of said shell.

4. A blotter comprising a body, a shaft eccentrically journaled to said body and having an offset journal portion, a roller rotatably mounted 20 on the journal portion, a shell of absorbent material removably mounted on said roller, means for limiting the rotation of the shaft in either direction to permit positioning of the shell laterally of the body or in alignment therewith, means 25 to engage said shaft for holding the latter against accidental rotation in either of the positions of said shell, and spring means carried by the roller to engage the shell to prevent accidental removal of the shell from the roller.

LOUIS DUNNING.
